**APPARATUS FOR CUTTING RECESSES
IN A TIMBER**

 Kristian Viktor Jeppesen, Gladsaxevej 36-44,
Soborg, Denmark

 Original application Sept. 5, 1962, Ser. No. 221,526.
Divided and this application Dec. 3, 1963, Ser. No.
327,638

8 Claims. (Cl. 144—133)

This invention relates to a method of joining timbers or planks meeting at right angles in a wall structure in which each wall comprises a plurality of timbers placed edgewise one atop another and joined with each other by means of a key-and-groove connection, and in which the joints between the timbers of one wall are vertically offset relative to those of the adjoining wall, each timber having a recessed area circumscribing the timber to form a connecting portion which is adapted to be engaged in corresponding recesses of two adjoining timbers of the adjoining wall. This application is a division of my co-pending application Serial Number 221,526, filed September 5, 1962, now abandoned.

In the past, the recesses have been so made as to form a connecting portion of substantially rectangular cross-section presenting an upper and a lower horizontal face. This method presents the drawback that the connection between timbers is not sealed because as a practical matter there has to be a clearance at least between the upper and lower faces, respectively, of one connecting portion and the abutting faces of the connecting portions of the timbers of the adjacent wall. This drawback results in a connection which is insufficiently rigid and usually necessitates the use of corner posts in such wall structures.

The present invention aims to remedy this drawback by having the upper side of the connecting portion ridged with two inclined surfaces terminating in a rounded edge extending longitudinally of the timber, together with a recess in the lower side of the connecting portion adapted to cooperate with the upper ridge of the connecting portion of the next lower adjoining timber of the adjoining wall. This provides a completely tight joint and makes the wall structure so rigid as to render corner posts completely superfluous.

In order to further increase the rigidity of the wall structure and to obtain a satisfactory appearance of the connections, the lateral or side recesses may, in accordance with the invention, be formed with an upper and a lower portion, each terminating in rounded ends meeting at the horizontal longitudinal central plane of the timber and having a radius equal to or slightly less than half the lateral thickness of the timber.

The invention also provides an apparatus for producing such a recessed timber. The apparatus comprises a frame, means on the frame for clamping and positioning the timber, a slide mounted on the frame for vertical movement and carrying a rotary cutter adapted to effect an obliquely upwardly and forwardly directed movement and subsequently an obliquely downwardly and forwardly directed movement to form the upper region of the recessed area whereby the upper side of the connecting portion is ridged and a rotary cutter mounted on the frame adapted to form the lower region of the recessed area whereby the lower side of the connecting portion is recessed during vertical movement of the slide.

This construction provides an efficient apparatus which will make all recesses in one operation.

In order to obtain the correct movement of the cutter for cutting the upper region of the recessed area this cutter may be mounted at the ends of a table projecting forwardly from the slide, two pairs of arms being mounted

2

for swinging movement at the rear end of the table and being pivotally connected with a supporting member secured to the slide, in such manner that the pairs of arms in the inoperative position of the table extend upwardly and rearwardly, and one pair of arms is provided with a substantially laterally projecting arm connected with hydraulic means, and a coil spring has one end connected with the supporting member and its opposite end with the table.

10 In order to enable the opposed cutters to be easily moved away from and towards each other during vertical movement of the slide, for cutting the upper and lower, lateral recesses of the timber, these cutters may, in accordance with the invention, each be mounted in pivotal arms mounted on a bracket projecting from the slide and connected with each other by means of a spring which acts to urge the arms away from each other, means being provided for urging the arms towards each other against the spring action at certain intervals.

15 20 One example embodiment of the invention will now be described with reference to the accompanying drawings, in which:

FIGURE 1 is a side view of part of a timber according to the invention, showing the recesses and connecting portion;

25 FIGURE 2 is a sectional view along the line II—II in FIGURE 1;

FIGURE 3 is a front view of an apparatus embodying the invention; and

30 FIGURE 4 is a side view of the same apparatus without the frame.

FIGURES 1 and 2 illustrate a timber 1, all four sides of which are provided with recesses to form a connecting portion 2. The upper side of connecting portion 2 is 35 rounded with its crown extending longitudinally of the timber. FIGURE 2 shows the upper side of connecting portion 2 ridged to provide inclined surfaces 3 and 4 terminating in a rounded edge 5. The lower side of the plank 1 is provided with a corresponding recessed region 40 extending transversely of the timber and having a pair of inclined surfaces 6 and 7 which meet at a rounded corner 8. When connecting two walls extending at right angles to each other, each timber will be supported with the surfaces 6 and 7 of the lower recess upon the upper inclined surfaces 3 and 4 of the upper recess of the next lower adjoining timber in the adjoining wall.

45 These recesses in the plank may be made automatically by means of the apparatus illustrated in FIGURES 3 and 4.

50 55 The apparatus comprises a frame 9 supporting a table 10 having a positioning rail 11, against which the timber 1 to be cut, is secured. Frame 9 is at either side provided with vertical guiding rods 12 for slidably receiving 60 slide bearings 13 secured to a slide 14 which is thus vertically slidable along the rods 12.

55 65 A rearwardly extending supporting member 15 is secured to the slide 14 and carries two pairs of pivotal arms 16 and 17, the upper ends of which are pivotally connected with a table 18. An electric motor 19 is supported upon the table 18 for driving a rotary cutter 21 mounted at the forward end of the table 18 which projects from the front side of the slide 14. The driving connection comprises a belt 20. The pair of arms 17 are formed as bell crank levers and have integral with them another pair of arms 22 which are pivotally connected with a piston rod 24 of a piston mounted for sliding movement in a cylinder 23. A spiral spring 25 has its inner end connected with the rearward end of table 18 and its outer end connected with the supporting member 15 in such a manner as to be under tension in the rearmost, inoperative position of the table 18, as shown in FIGURE

4. The cutter 21 is adapted to cut the upper region of the recessed area, including the surfaces 3 and 4.

For cutting the lower region of the recessed area comprising the inclined faces 6 and 7 there is provided another rotary cutter 26 which is mounted on an arm 27 secured to the slide 14, the axis of the cutter being situated vertically below the longitudinal central plane of the timber 1 clamped in the machine. The arm 27 further extends somewhat rearwardly of the slide 14 and carries an electric motor 28 for driving the cutter 26.

As previously mentioned, the lateral recessed regions of the timber 1 are suitably so formed as to comprise on either side of the timber a lower, lateral recessed portion 29 having a rounded upper end 30 with a radius equal to or slightly less than half the lateral thickness of the timber, and an upper, lateral recessed portion 31 having a rounded lower end 32 with a radius equal to half of slightly less than half the lateral thickness of the plank as seen in FIGURES 1 and 2, the said rounded ends meeting each other at the longitudinal central plane of the timber. The lateral recesses are cut by means of a pair of opposed, rotary cutters 33 and 34, each mounted on a vertical arm 35 and 36, respectively. The arms 35 and 36 are pivotally mounted on a bracket 37 projecting from the slide 14 so as to be capable of swinging movement towards and away from each other. A curved spring 38 is secured to the arms 35 and 36 and acts to urge them away from each other. Each arm 35, 36 is provided with a laterally projecting arm 39 and 40, respectively, which are connected with each other by means of a lever system which controls the movements of the arms 35 and 36 relative to each other in such a manner that both arms are simultaneously pivoted towards or away from each other. This lever system may comprise a short two-armed lever 41 pivotally mounted at its middle point on an upright 42 on the bracket 37 and having its ends pivotally connected with the lateral arm 39 of the arm 35 and with one end of a connecting rod 43, respectively, the opposite end of which is connected with the lateral arm 40 of the arm 36. The arm 40 is, furthermore, pivotally connected with one arm of a two-armed lever 44 pivotally mounted in the bracket 37 and provided with a roller 45 at its other arm which is adapted to cooperate with an upper cam member 46 and a lower cam member 47 secured in frame 9. An upright 48 extends upwardly from the bracket 37 and carries a pivotal, two-armed lever one arm 49 of which is provided with a roller 50 adapted to cooperate with a cam 51 secured on the frame 9, and the other arm 52 of which is adapted to engage a projection 53 on the arm 35 so as to hold the arms 35 and 36 in their closest relative position.

The timber 1 is clamped to the table 10 against the guiding rail 11 by means of a bell crank lever mounted on the table 10 and carrying on one arm 54 a clamping shoe 55, whereas its other arm 56 is pivotally connected with a piston rod 57 of a hydraulic cylinder 58.

The operation of the machine described is as follows:

A timber 1 is placed on the table 10 against the positioning rail 11. The operator pulls a starting lever 59 to start the machinery, and oil is supplied from an oil pump (not shown) to the cylinder 58, whereby the clamping shoe 55 is pressed against the timber 1 to hold the same firmly.

In its inoperative position, the slide 14 is in an intermediate position in which the cutter 21 is on a somewhat higher level than the timber 1 and the piston of the cylinder 23 is not in its lowermost position. When the operating lever 59 is pulled, the oil under the piston in the cylinder 23 is first allowed to escape, whereby the piston rod 24 is caused to move downwardly and the slide 14 including all parts mounted thereon is lowered until the frame abuts against a lower stop. In this position of the slide, the piston rod 24 has not yet attained its lowermost position. Therefore, the spiral spring 25

will act upon the table 18 in such a manner that, due to the presence of the levers 16 and 17, the cutter 21 will move upwardly and forwardly in an inclined path, until the levers 16 and 17 are in vertical position, and subsequently move obliquely forward and downward. By this movement the cutter 21 cuts the upper recessed region of the timber 1. Subsequently, pressure oil is supplied to the cylinder 23 so as to lift the piston rod 24, whereby the table 18 is moved back to its initial position and the slide 14 is lifted.

During the aforesaid downward movement of the slide, the roller 45 engages the lower cam 47 so as to cause the levers 35 and 36 to move towards each other, thereby permitting the arm 52 to engage the projection 53 of the lever 35. When the slide 14 has attained a certain level, the opposed cutters 33 and 34 will effect cutting of the lower, lateral recesses 29, 30. When these recesses have been completed, the roller 50 has attained such level as to engage the cam 51, whereby the arm 52 is disengaged from the projection 53 of the lever 35 so that the levers 35 and 36 and the cutters 33 and 34 are permitted to move away from each other under the action of the spring 38 while the cutters are lifted past the point where the upper and the lower lateral recesses meet each other. The roller 45 of the two-armed lever 44 then engages the upper cam member 46 so that the cutters 33 and 34 are again moved towards each other and the lever 52 again engages the projection 53. Now the upper lateral recess 31, 32 is cut during further upward movement of the slide 14. This movement also causes the cutter 26 to cut the lower recessed region in the plank 1. Finally, the slide 14 abuts against an upper stop, whereby the oil is allowed to escape from the cylinder 23, until the slide 14 has attained the position indicated in FIGURE 4. At the same time oil is allowed to escape from the cylinder 38 so that the clamping shoe 55 is removed from the timber 1 to enable the latter to be removed or displaced.

In order to allow for adjustment of the aforesaid upper and lower stops for the slide 14, the latter may be formed with an upper recess 60 which is engaged by a pair of pins 61 and 62, each mounted on a two-armed lever 63 and 64, respectively, mounted pivotally in frame 9 for cooperation with screw spindles 65 and 66 engaging screw nuts 67 in frame 9 and provided with hand wheels. One lever 63 acts as a lower stop, when the upper edge 68 of the recess 60 abuts against pin 61, while the other lever acts as upper stop when the lower edge 69 of the recess 60 abuts against pin 62.

The apparatus described may be modified in various respects within the scope of the appended claims. Thus, for instance, the control of the various movements may be effected in ways other than that described.

What I claim is:

1. An apparatus for producing circumscribing upper and lower recessed areas in a timber to define a connecting portion of reduced cross-section to permit interlocking use of several of the timbers to form wall sections comprising, a frame, means on the frame for clamping and positioning the timber, a slide mounted on the frame for vertical movement thereupon from an inoperative rest position and carrying a first rotary cutter, means for operating the cutter to effect an obliquely upwardly and downwardly directed movement and subsequently an obliquely downwardly and forwardly directed movement during downward vertical positioning of the slide to form the upper region of the recessed area and to define downwardly sloping upper walls of the connecting portion whose planar surfaces lie longitudinally of the timber, a second rotary cutter mounted on the frame below the first rotary cutter, means for operating the first rotary cutter to form the lower region of the recessed area and to define downwardly sloping upper walls in the lower area of the connecting portion whose planar surfaces are transverse to the longitudinal length of the timber, the lower

region of the recessed area being formed during upward vertical positioning of the slide, a pair of horizontal, axially opposed rotary cutters mounted on the frame, means causing the axially opposed rotary cutters to cut a pair of lower lateral recesses in the timber during vertical downward movement of the slide, means for moving the axially opposed rotary cutters apart and subsequently towards each other for cutting a pair of upper lateral recesses in the timber, the first cutter for forming the upper region of the recessed area further being mounted at the end of a table projecting downwardly from the slide, the table having an operative position and an inoperative position, two pairs of arms being mounted for swinging movement at the rear end of the table and being pivotally connected with a supporting member secured to the slide in such a manner that the pairs of arms in the inoperative position of the table extend upwardly and rearwardly, one pair of said arms being provided with a substantially laterally projecting arm connected with a vertically operating hydraulic means, and a spiral spring having one end connected with the supporting member and the other end connected with the table, whereby upon downward movement of the hydraulic means and the slide is moved downward and the spring causes the table to rotatably move about the pairs of arms to position the first cutter in operative relation with the timber.

2. An apparatus as defined in claim 1 wherein opposed rotary cutters are each mounted in pivotal arms mounted on a bracket projecting from the slide, the pivotal arms being connected with each other by a spring acting to urge the arms away from each other.

3. An apparatus as defined in claim 2 wherein one of the pivotal arms carrying the opposed rotary cutters is pivotally connected with one end of a two-armed lever pivotally mounted in the bracket the other end of said two-armed lever being pivotally connected with a connecting rod which connecting rod is in turn connected with the other of said pivotal arms carrying the opposed rotary cutters, said other pivotal arm being also pivotally connected with one arm of a second two-armed lever mounted on the bracket said second two-armed lever being provided on its other arm with a roller adapted to cooperate with a cam associated with the frame.

4. An apparatus as defined in claim 2 wherein a bell crank lever is pivotally mounted on an upright on the bracket, one end of said lever being adapted to engage a projection on one of the pivotal arms carrying the opposed rotary cutters for holding said pivotal arms in their

closest position one with another the other arm of the bell crank lever carrying a roller adapted to cooperate with cam means on the frame for disengaging the bell crank lever from said projection.

5. An apparatus as defined in claim 1 wherein the cutter for forming the lower region of the recessed area is rotatably mounted on an arm secured to the slide, in such a manner that its axis is situated below the level of the opposed rotary cutters in the center plane of the timber when clamped.

10 6. An apparatus as defined in claim 1 wherein the inoperative position of the slide is such that the cutter for forming the upper region recessed area is situated at about the level of the timber when clamped, and including a 15 hydraulic piston suitably spaced from the bottom of its cylinder for vertically displacing the slide.

7. An apparatus as defined in claim 1 including means 20 operable by an operative lever for supplying a hydraulic medium to a cylinder having its piston operatively connected with the timber clamping means and for allowing the hydraulic medium to escape from the cylinder operating the slide to cause the slide to be lowered to engage a lower stop, for subsequently supplying a hydraulic medium to said cylinder to lift the slide to engage an 25 upper stop, and for finally allowing hydraulic medium to escape from the cylinder for lowering the slide to the inoperative position thereof and from the cylinder operating the clamping means for the timber.

8. An apparatus as defined in claim 1 wherein the slide 30 has an upper recess engaged by a pair of pins, each of the pins being secured to pivotal levers mounted on the frame, one of said pins being adapted to engage the upper edge of the recess to constitute a lower stop and the other of said pins being adapted to engage the lower edge of 35 the recess to constitute an upper stop, the pivotal levers being each pivotally connected with a screw spindle cooperating with a nut mounted in the frame.
